ROBERT M. HUDDLESTON, OF SAN FRANCISCO, CALIFORNIA.

STOP-MOTION FOR CANNING MACHINERY.

1,245,922.

Specification of Letters Patent.

Patented Nov. 6, 1917.

Application filed October 19, 1914. Serial No. 867,556.

To all whom it may concern:

Be it known that I, ROBERT M. HUDDLESTON, a citizen of the United States, residing in the city and county of San Francisco and State of California, have invented a new and useful Improvement in a Stop-Motion for Canning Machinery, of which the following is a specification.

My invention relates to a stop motion device for canning machinery, wherein parallel cams operate in unison with the machine while working properly and wherein one of the cams is retained in such a position that the other cam will automatically operate to release the machine from the driving mechanism; and the object of my invention is to provide improved means for automatically disengaging the machine from the driving mechanism thereof when certain portions of the machine fail to operate properly.

I accomplish this feature by means of the device disclosed in the drawings forming a part of the present specification, wherein like characters of reference are used to designate similar parts throughout the said specification and drawings, and in which—

Figure 1 is a broken side elevation of the machine disclosing the device attached thereto, also disclosing the manner in which the cans are fed into the machine and the various cams by means of which the several parts of the machine are operated.

Fig. 2 is a broken plan view of the machine disclosing my device attached thereto, the driving clutch by means of which the machine is driven and the various parts by means of which the cans are fed to a filling position.

Fig. 3 is an enlarged broken plan view of the can feeding mechanism on an enlarged scale, the full lines indicating one extreme position of the said mechanism and the dotted lines indicating the other extreme position, disclosing the manner in which the parallel cams operate in unison with the can feeding mechanism when the said mechanism is unobstructed.

Fig. 4 is an enlarged sectional plan view of the parallel cams in the position indicated in Fig. 3, disclosing the manner in which the operating peripheries of the said cams coincide and do not affect the operating pin when the several parts of the can feeding mechanism are operating properly.

Fig. 5 is a view similar to Fig. 3 but disclosing the slide operating mechanism with-

held and the top parallel cam rotating on its axis on the bottom parallel cam to operate the releasing pin.

Fig. 6 is an enlarged plan view of the parallel cams in the position disclosed in Fig. 5.

Fig. 7 is a vertical sectional view taken on line 7—7 of Fig. 6 of the drawings, disclosing the manner in which the upper cam is rotatably mounted upon and eccentric to the lower cam.

Fig. 8 is an enlarged front elevation of the tripping lever disclosing the manner in which it is operated by the releasing pin.

Fig. 9 is a broken side elevation of the clutch releasing mechanism.

In order to fully comprehend the invention it is necessary to describe that portion of a certain can filling machine by means of which the stop motion is operated.

Referring to the drawings, the numeral 1 is used to designate the frame of the machine, to which is rigidly secured a lateral shaft 2 upon which is rotatably mounted a pinion 3, said pinion 3 being rigidly connected to a disk 4 which is arranged to compress between itself and the surface of a driving pulley 6, the friction disk 7 provided with cork inserts 8.

The disk 4 is held in engagement with the driving pulley 6, so as to operate the machine, by means of the yoke 9 which is pivotally mounted at its lower end, on a bracket 12, the upper end of the said yoke 9 being provided with a link 14 which is in turn pivotally connected to the operating lever 16, pivotally mounted upon a bracket 17, so that when the said lever 16 is moved away from the machine it will cause the link 14 to move the yoke 9 outward and in turn the yoke 9 will move the disk 4 on the pinion 3, into engagement with the driving pulley 6 and the disk 7 thereof, thereby rotating the pinion 3 and the gear 18 with which the pinion 3 is in mesh.

The gear 18 is rigidly secured to a driving shaft 20 which is provided with a cam 22 arranged to engage the lower end 24 of a lever 26 pivotally mounted as at 27 to a suitable bracket 28 secured to the frame 1.

As the cam 22 is rotated it imparts a reciprocating movement to the lever 26, which movement is imparted to a connecting rod 31 pivotally connected to the upper end of the lever 26 and to a lever 32, the latter being provided with a pawl 34 arranged to

engage the ratchet 36 of the can feeding member 37, said reciprocating movement being thereby arranged to impart an intermittent rotation to the said can feeding member 37 in the direction indicated by the curved arrow in Fig. 1 of the drawings.

As the can feeding member 37 rotates, it receives the cans 38 from the runway 39 and conveys the said cans one at a time, onto a slide 40 slidably mounted within a table 45 of the frame 1.

The slide 40 is provided with a vertical extension 41 which is arranged to engage a can 38 on the slide 40 and convey the said can 38 to the horn 54 of the feeding hopper 55, by means of the following mechanism.

A suitable link 42 is pivotally connected to the slide 40 and to the arm 43 of a bell crank lever pivotally mounted as at 44 upon the under side of the table 45. The other arm 46 of the bell crank lever is provided with a rotatable swivel 47 arranged to slidably engage a reciprocating rod 48 which is pivotally secured to a lever 49 arranged to be engaged by a second cam 51 rigidly secured to the drive shaft 20.

From the above it is evident that as the driving pulley 6 rotates the pinion 3, a rotary movement is imparted to the gear 18 and shaft 20 thereof, which movement, by means of the can feeding member 37 and connections thereto, and the slide 40 and connections thereto, will convey cans from the runway 39 to the said slide 40.

During the return movement of the rod 31, and while the can feeding member 37 is at rest, being held against rotation by the dog 35, the cam 51 and connections thereto, will operate the slide 40 and carry the can 38 onto the horn 54 of the hopper 55.

A plunger or other suitable stuffing mechanism not shown, fills the can 38 on the slide 40 and returns the said can 38 with the return movement of the said slide 40 to the normal position of the said slide as shown in Fig. 2 of the drawings.

Briefly, every movement of the can feeding member 37 will convey an empty can 38 from the runway 39 onto the slide 40 and simultaneously convey a filled can from the slide 40 onto the delivery chute 50.

During this movement, cans very frequently become jammed between the vertical extension 41 of the slide 40 and the horn 54 of the hopper 55, and before the machine can be stopped it sometimes happens that several cans will be piled up and jammed together. When cans are jammed in this manner it necessitates considerable loss of time and also a loss of material until the machine can be again placed in proper operating order. Sometimes the cans and connections are broken by the strain and this incapacitates the machine until repairs can be made.

The present invention provides a means whereby the machine is instantly disconnected from the driving wheel 6, by releasing the link 14 connected to the lever 16 as soon as any undue resistance is applied to the slide 40 by reason of a can 38 becoming jammed therein or from any other reason.

This means may be described as follows:

A lever 57 is pivotally mounted upon the frame 1 as at 58 and is provided with a shoulder 52 arranged to engage the under side of the link 14 and thereby retain the lever 16 in a position where the yoke 9 will retain the disk 4, secured to the pinion 3, in engagement with the disk 7 of the driving pulley 6, as disclosed in Fig. 2 of the drawings.

To the lower end of the lever 57 is pivotally connected a rod 61 which is slidably mounted within a suitable staple 62, the free end of the rod 61 being provided with a beveled end 63, the purpose of which will hereinafter be more fully set forth.

A suitable spring 64 is connected to the rod 61 and staple 62 and serves to normally retain the shoulder 59 of the lever 57 under the link 14. The beveled end 63 of the rod 61 is also normally held, by means of the spring 64, against the frusto-conical end 66 of a releasing pin 69 slidably mounted within the housing 67 of a suitable bracket 68. The releasing pin 69 is provided with a collar or annular flange 71 and between the said flange 71 and the end of the housing 67 is interposed a spring 72 arranged to normally retain the inner end of the releasing pin 69 against the operating periphery or surface of the upper cam 73 which is eccentrically and as at 74, pivotally mounted upon a second cam 76, said cam 76 being in turn pivotally mounted within the bracket 68.

A connecting rod 77 connects the cam 76 with a collar 78 slidably mounted on the rod 48 which operates the slide 40, while a similar connecting rod 79 connects the cam 73 with the end of a rod 81 which is in turn pivotally connected to a collar 85 upon the rod 48. The collar 85 is held against movement on the rod 48 by means of a suitable stud 82.

A connecting rod 83 connects the outer end of the rod 81 with a collar 84 on the rod 48 which collar 84 is held against movement on the said rod 48 by means of a suitable stud 86.

By loosening the stud 82 and moving the collar 85 thereon to the left, the connecting rod 83 will swing outward on the stud 86 and thereby cause the link 79 to move the cam 73 inward without disturbing the cam 76. In this manner the relative operating positions of the cams 73 and 76 may be adjusted.

Interposed between the collar 78 on the rod 48 and a collar 89 on the end of the said

rod 48 is a spring 88 which serves to keep a collar 90, rigidly secured to the rod 48, normally against the swivel 47 which is pivotally mounted upon the arm 46 of the bell crank lever pivotally mounted upon the table 45.

In this manner the said bell crank lever is caused to normally move when the rod 48 moves.

10 The operation of the automatic releasing device is as follows:

While the machine is operating properly, that is, the member 37 is carrying and removing cans 38 to and from the slide 40, the movement of the reciprocating rod 48 will cause by means of the various connecting rods 77, 79, 81 and 83, the cams 73 and 76 to move in unison on the pivot of the cam 76 and the releasing pin 69 will not be affected (as disclosed in Figs. 3 and 4 of the drawings.)

Should an imperfect or bent can or any other obstruction, unduly retard the action of the slide 40, the arms 43 and 46 of the bell crank lever will likewise be held against movement and the connecting rod 77 will likewise prevent a further movement of the cam 76. As the movement of the rod 48 however, is continued by the action of the lever 49 and cam 51 on the shaft 20, such movement will not only be taken up by the compression of the spring 88 without straining or breaking the bell crank lever connected to the slide 40, but the said continued movement of the said rod 48 will cause the connecting rod 79 to partially rotate the cam 73 on the center 74 and thereby cause the said cam to move the releasing pin 69 against the tension of the spring 72 and also against the beveled portion 63 of the rod 61, as disclosed in Figs. 5 and 6 of the drawings.

As the frusto-conical end 66 of the releasing pin 69 moves against the beveled end 63 of the rod 61 the said rod 61 will cause the lever 57 to release the link 14 and the yoke 9 will release the disk 4 from engagement with the disk of the driving pulley 6, such release being facilitated by the resiliency of the cork inserts 8 of the disk 7.

50 It is obvious from the foregoing that I have provided improved means for instantly releasing the machine from the driving mechanism thereof should the several parts thereof cease to operate properly by means of a can being jammed therein or for any other purpose.

Briefly, the operating surface or periphery of the cam 73 that engages the releasing pin 69 will be retarded as rapidly by the rotation 62 of its eccentric center on the cam 76 as the said surface is forwarded by the action of the rod 48 and connecting rod 79 as long as both cams operate in unison, that is to say, that the said periphery of the cam 73 will always 65 be concentric with the center of rotation of

the cam 76 as long as both cams operate in unison.

When the movement of the cam 76 is retarded by reason of the slide 40 becoming jammed, the cam 73 will rotate in its center 74, now stationary, and the said cam will move in the direction indicated by the curved arrow in Fig. 6 of the drawings and move the releasing pin 69 against the beveled surface 63 of the rod 61.

Inasmuch as the driving power of the machine is thus instantly released, it is evident that the machine will be stopped and the member 37 will cease to feed cans to the slide 40.

Having thus described my invention what I claim as new and desire to secure by Letters Patent is—

1. In a stop motion the combination of a driving element; driven mechanism; a suitable clutch to normally disengage the driven mechanism from the driving element; a lever having a shoulder thereon to engage and retain the clutch in driving relation with the driven mechanism; a rod slidably mounted upon the machine and pivotally connected with one end of the lever, the other end of said rod being beveled; a releasing pin slidably mounted within the machine and having a frusto conical end to engage the beveled end of the rod; a cam pivotally mounted within the machine and operatively connected to the driven mechanism; and a second cam eccentrically mounted upon the first mentioned cam and arranged to engage and operate the releasing pin and the slidable rod to release the clutch and thereby disengage the driving element from the driven mechanism when an undue resistance is offered to the said 100 driven mechanism.

2. In a stop motion the combination of a driving element; a driven mechanism; a feeding mechanism operatively connected to the driven mechanism; a clutch secured to the driving element to normally disengage the driven mechanism; a lever to normally retain the clutch in driving relation with the driven mechanism; a rod slidably mounted upon the machine and having a beveled end and the other end pivotally connected to the clutch retaining lever; a releasing pin slidably mounted within the machine and having a frusto-conical end to engage the beveled end of the rod; a cam pivotally mounted within the machine and operatively connected with the feeding mechanism; and a second cam eccentrically mounted upon the first mentioned cam and operatively connected to the driven mechanism and arranged to operate the releasing pin and slid- 120 able rod and thereby release the clutch from the driven mechanism when an undue resistance is offered to the feeding mechanism.

3. In a stop motion the combination of a 130

- driving element; a driven mechanism; a feeding mechanism; a reciprocating rod yieldingly connecting the feeding mechanism to the driven mechanism; a clutch secured to the driving element and arranged to normally disengage the driven mechanism; a lever pivotally mounted upon the machine to retain the clutch in engagement with the driven mechanism; a rod slidably mounted upon the machine and pivotally connected to the lever at one end and having the other end beveled; a releasing pin slidably mounted within the machine and having a frusto-conical end to engage the beveled end of the rod; a cam mounted upon the machine and operatively connected with the feeding mechanism; a second cam eccentrically mounted upon the first mentioned cam and operatively connected to the driven mechanism, said second mentioned cam being arranged to operate the releasing pin and slidable rod and lever connected thereto to release the clutch from the driven mechanism when the first mentioned cam is held stationary by an undue resistance offered to the feeding mechanism.
4. In a stop motion the combination of a driving element; a driven mechanism; a feeding mechanism; a reciprocating rod yieldingly connecting the feeding and driven mechanisms; a suitable clutch secured
- 5 10 15 20 25 30

to the driving element and arranged to normally disengage the driven mechanism; a lever arranged to retain the engage of the clutch with the driven mechanism; a slide- 35 able rod connected at one end with the lever and having the other end thereof beveled; a slideable releasing pin having a frusto- conical end to engage the beveled end of the slideable rod to move said rod to operate the lever and thereby release the clutch; a cam operatively connected to the reciprocating rod at the driven mechanism end; a second cam eccentrically mounted upon the first mentioned cam and slideably connected to the feeding mechanism end of the reciprocating rod; and means for operating the first mentioned cam with the feeding mechanism whereby said cam may be held stationary when an undue resistance is offered to the feeding mechanism and thereby cause the eccentrically mounted cam to operate the releasing pin and release the clutch from the driven mechanism.

50 55 In witness whereof I hereunto set my signature in the presence of two subscribing witnesses.

ROBERT M. HUDDLESTON.
